UNITED STATES PATENT OFFICE

CHARLES FOSTER CORBETT, OF EDMONTON, ALBERTA, CANADA

TOBACCO PIPE

Application filed July 20, 1929. Serial No. 379,763.

This invention relates to improvements in tobacco pipes and the object of the invention is to provide an improved form of tobacco pipe which will be exceptionally convenient and pleasant to use and in which particles of tobacco or ash are prevented from being drawn into the stem.

A further object is to arrange the air and smoke passages in the bottom of the bowl in such a manner as to distribute the draft over a greater area of the bottom and thereby prevent condensation from concentrating at one point and obstructing the draft.

A further object is to provide an improved construction whereby cleaning of the pipe will be facilitated.

The invention consists in the construction, all as hereinafter more particularly described, and illustrated in the accompanying drawings in which,

Figure 1 is a longitudinal sectional elevation of a pipe constructed in accordance with the present invention, the pipe being of the closed bowl type.

Figure 2 is a top plan view of a plug used in the improved pipe.

Figure 3 is a section on the line 3—3 of Figure 2.

Figure 4 is a longitudinal sectional elevation of the ordinary open bowl type of pipe constructed in accordance with the present invention.

In the drawings like characters of reference indicate corresponding parts in the different views.

The improved pipe comprises a bowl portion 10 and a stem portion 11, the bore 12 of the stem communicating with the bowl at a point spaced upwardly from the bottom of the bowl. The interior of the bowl is indicated by the numeral 13 and the bottom of the bowl is open for the full internal diameter thereof.

Associated with the bowl is a cylindrical plug 14 the diameter of which is such that the plug may be inserted into the bottom open end of the bowl in which position the plug will form a closure for the bottom of the bowl. The lower end of the plug is of in-

creased diameter at 15 to form a shoulder which engages the bottom of the bowl.

The plug 14 extends upwardly into the bowl to a point above the stem opening and the upper end of the plug is cupped at 16 said cupped portion 16 forming the bottom of the interior of the bowl when the plug is in position and the depth of the cupped portion 16 being such that the bottom thereof is below the stem opening.

The peripheral surface of the plug is formed with an annular groove 17 adapted to register with the bore 12 when the plug is in position and communicating with this annular groove 17 are a number of small passages 18 provided in the plug which extend downwardly from the groove 17 and communicate with the bottom of the cupped portion 16 of the plug, the diameter of these passages 18 being considerably less than that of the bore 12 of the stem 11.

In use air and smoke are drawn through the passages 18 in the plug and from thence into the annular groove 17 and pass around this groove and finally enter the bore 12 of the stem and in this way the draft is distributed over the bowl and is not concentrated at any one point thereof.

By making the passageways 18 considerably smaller than the bore 12 of the stem, particles of tobacco or ash are prevented from getting into the stem.

A further feature of the improved pipe is that condensation is trapped in the groove 17 and tends to fall back into the bottom of the bowl through the downwardly inclined passages 18 and therefore will not interfere with the draft.

The plug 14 is readily removable so that the interior of the bowl may be readily cleaned and also, when removed, the construction of the plug is such that all passages therein may be readily and conveniently cleaned.

From the foregoing it will be apparent that the invention provides an improved tobacco pipe whereby the objects set forth have been attained.

Various modifications may be made in this invention without departing from the spirit thereof or the scope of the claim, and there-

fore the exact form shown is to be taken as illustrative only and not in a limiting sense, and it is desired that only such limitations shall be placed thereon as are disclosed in the prior art or are set forth in the accompanying 5 claim.

What I claim as my invention is:—

A tobacco pipe comprising in combination with a bowl having a stem opening communicating therewith at a point spaced upwardly 10 from the bottom of the bowl, said bowl being open at the bottom for the full internal diameter thereof, of a plug adapted for insertion into the open bottom of the bowl to form a closure therefor and extending upwardly 15 into the bowl to a point above the stem opening, the upper end of the plug cupped, said cupped portion forming the bottom for the interior of the pipe bowl and the bottom of the cupped portion lying below the stem opening, 20 the periphery of the plug formed with an annular groove registering with the stem opening, and the plug formed with a plurality of downwardly inclined passages leading from the annular groove to the bottom of the 25 cupped portion, said downwardly inclined passages in the plug being of smaller diameter than that of the stem opening.

In witness whereof I have hereunto set my hand.

CHARLES FOSTER CORBETT.
